UNITED STATES PATENT OFFICE.

FRED W. HARGRAVE, OF SOUTH RIVER, AND JAMES A. WHEELER, OF SOMERSET COUNTY, NEW JERSEY, ASSIGNEES TO WILLIAM T. ELKINTON, OF PHILADELPHIA, PENNSYLVANIA.

METHOD OF FORMING FIREPROOF BUILDING CONSTRUCTION.

1,234,160.

Specification of Letters Patent. Patented July 24, 1917.

Application filed March 5, 1914. Serial No. 322,718.

To all whom it may concern:

Be it known that we, FRED W. HARGRAVE, a resident of South River, in the county of Middlesex and State of New Jersey, and 5 JAMES A. WHEELER, a resident of the county of Somerset, in the State of New Jersey, both citizens of the United States, have invented certain new and useful Improvements in Methods of Forming Fireproof Building 10 Construction, such as Doors, Trim, or the like, of which the following is a specification.

This invention relates to methods of forming fireproof building construction, such as 15 doors, trim, or the like, and it has special relation to the forming or production of articles designed to be used in fireproof building construction and which combine an artificial fireproof lumber or composition 20 and metallic elements.

Our improved method is adapted for effective employment or use in forming all 25 types of articles or devices for use in fireproof building construction, such as doors, door frames, window and sash frames, trim, or the like, and in the accompanying illustration of the method we have shown its application to the forming of one type of construction of fireproof doors.

Heretofore, in the forming of fireproof building construction of this class, combining an artificial fireproof lumber or composition and metallic elements, the artificial fireproof lumber or composition has been 35 molded and compressed into shape to produce a construction in which it forms the exterior surface of the door or other article, and the metallic elements have been contained within the interior space of such exterior composition structure, as bracing elements, for instance as shown and described 40 in the previous applications of James A. Wheeler, Serial No. 676,817, filed February 10, 1912, Serial No. 676,818, filed February 45 10, 1912, and Serial No. 770,809, filed May 31, 1913. Fireproof doors and other articles of this class have also been heretofore constructed with metallic casings in which are placed internal body structures of wood or 50 other material to form a bracing.

The object of our present invention is to provide a simple and improved method whereby such doors or other articles for use in fireproof building construction may be

readily and economically formed with an 55 external metallic casing or sheathing inclosing and carrying an internal body structure formed of an artificial fireproof lumber or composition, and to these ends the leading feature of our improved method consists in the molding of the artificial fireproof lumber or composition directly within the external metallic casing or sheathing and compressing and drying the composition in a rigid structure within the mold formed by 60 the external metallic casing or sheathing of the finished article, substantially as herein-after described and particularly pointed out in the claims.

In carrying out our improved method, the 70 internal fireproof body structure, which is molded and compressed and dried in a rigid structure within a mold formed by the external metallic casing or sheathing of the finished article, is formed of artificially 75 united substances having a fireproof quality and which are solidified and compressed and dried in a rigid structure so that sufficient density and strength will be imparted to effectually resist the strains and other conditions which are encountered in the employment of the device or article in building constructions. For this purpose, we prefer to use the composition which is commercially 80 known as "alignum" and which is constituted 85 by a suitable filler including asbestos and combined with a fireproof binder to produce a plastic substance which is molded into shape and compressed and dried in a rigid structure, and which forms a rigid non-metallic composition of low heat conductivity and undefeatable by heat, said 90 "alignum" composition being described in its general characteristics in the patent to James A. Wheeler, for an improved method 95 of forming fireproof slabs or boards, No. 1,048,616, dated December 31, 1912. As described in said patent, this artificial lumber or composition material preferably consists of a filler including burnt clay broken into 100 small particles or crushed into a pulverized condition though any other suitable or adapted substance may be employed, and said filler is then mixed or compounded with asbestos in suitable or desired proportion, and there is then added to the compound or mixture a relatively small proportion of a suitable soluble fireproof binding 105

- material which will permanently unite the elements of the mass, for instance the binding material preferably consists of or includes silicate of soda. After the plastic mass is compounded and thoroughly mixed to a proper consistency, it is adapted to be molded into the desired general shape or form, and is then compressed and hardened and dried to the desired degree of density.
- 5 The fireproof composition of the characteristics as just stated is therefore adapted to be conveniently and economically molded within the exterior metallic casing or sheathing of the finished article and compressed and dried in a rigid structure within the mold formed by said external metallic casing or sheathing, in carrying out the improved method constituting our present invention.
- 10 In the accompanying drawings—
- Figure 1 is a side view of a press such as may be employed in carrying out the improved method herein described, showing the arrangement of the parts of a door structure therein and subject to the method of forming and compressing the internal fireproof composition body structure within the mold constituted by the external metallic casing or sheathing, parts being shown in section
- 15 to illustrate the structural features.
- Fig. 2 is a detail cross-section, on an enlarged scale, taken through the casing or sheathing and the composition therein and the molding and compressing elements.
- 20 Fig. 3 is a top or plan view, illustrating the base construction within which the external metallic casing or sheathing is placed and showing the latter therein in position to form the mold.
- 25 Fig. 4 is a detail cross-section, on an enlarged scale, through a complete door as formed by the two corresponding half-sections produced under our improved method.
- 30 Corresponding parts in all the figures are denoted by the same reference characters.
- Referring to the drawings, 1 designates a type of press which may be employed in carrying out our improved method. Said press preferably comprises steam chambers, 35 as at 2—2, for the purpose of producing the drying action upon the fireproof composition or substance which is molded and compressed and solidified and hardened within the mold formed by the external metallic casing or sheathing of the finished article.
- 40 Into said chambers steam is introduced by means of communicating tubes or pipes, 3, and the press has a suitable bed or base, 4, and a follower, 5, controlled by a screw, 6, operating in a cross-head, 7, to exert the desired degree of pressure in the molding and drying operation.
- 45 In the preferred arrangement for carrying out our improved method for forming fireproof doors or analogous articles, as
- herein shown, the steam chamber is mounted above the bed 4, and its top surface forms a table, as at 8, upon which a smooth metallic plate or sheet, 9, is placed. A metallic frame or form, 10, conforming to the outline or shape of the door or analogous article, is carried by the base plate 9 and is preferably constituted by a series of metallic bars, 11, projecting at the top surface of the plate 9 and detachably or adjustably secured thereto by screws or bolts, 12, said bars being relatively arranged to form a frame somewhat larger than the size of the door which is to be produced. Metallic strips, 14, preferably formed of steel are placed within the frame 10 to occupy the space between the inner edge thereof and the edge portion of the door which is to be produced, these strips being in loose position and resting upon the base plate 9 so that they are readily removable to enable the removal of the finished half-section of the door after the molding and pressing and drying operation.
- 50 A metallic plate or sheet, 15, adapted to form the external casing or sheathing of the finished door is placed within the form constituted by the surrounding strips 14. This casing sheet is substantially pan-shape and is bent to form a base portion, as at 16, resting upon the top surface of the base plate 9 and adapted to form the side surface of the door, and upwardly-turned projecting edge portions, 17, resting against the strips 14 and adapted to form the edge portion of the door, the top edges of said projecting portions 17 being preferably turned inwardly at an angle to form a projecting retaining flange, as at 18, to facilitate the retention of the fireproof composition during the molding operation and after it is compressed and dried in position.
- 55 The plastic fireproof composition, as hereinbefore set forth, which constitutes the internal body structure of the completed door construction, is shown at 19, and is troweled or otherwise filled in to a suitable height into the mold formed by the metallic plate or sheet 15 which constitutes the external casing or sheathing of the completed door structure. Suitable plungers or cores, 20, of proper and desired size and shape, are then placed and relatively positioned upon the plastic mixture 19 within the casing mold 15, these plungers being of proper contour and spaced as desired to form the internal body shape and structure which is constituted by the fireproof composition. Said plungers are provided with vertical perforations 21, to permit the moisture or steam to effectually escape from the plastic composition mass 19 during the molding and compression thereof to harden and dry the same. A sheet of wire netting, as at 22, is preferably placed to extend over the bottom of the respective plungers or cores 20, to pre-

5 vent the plastic composition 19 from entering the perforations 21, which wire netting may be left in the composition body structure 19 after the compressing and drying operation thereon.

Over the top of the set of plungers or cores 20, and covering the full top area of the casing mold 15, is placed a metallic plate, 23, having perforations, 24, to permit 10 the effective escape of the steam or moisture passing thereto from the underlying perforated plungers and the plastic composition 19. Said perforated plate 23 also acts as a former for the top surface of the internal 15 composition body structure 19. The perforations of the plate 23 are relatively smaller than the perforations 21 of the plungers 20, inasmuch as it is desirable to leave a smooth and approximately even surface 20 at the top of the internal composition body structure 19, which surface will not be impaired by the relatively-small perforations of the former plate 23, while the provision of the relatively-large perforations in the 25 plungers or cores 20 permits the effective escape of the moisture or steam from the body mass of the plastic 19.

Over the perforated plate 23 is placed wire netting preferably consisting of a plurality of two or more crossed sheets of netting, as at 25—25, to permit the moisture or steam escaping at the top of the plate 23 to pass off laterally from the elements arranged in the press. Upon the wire netting 35 25 is placed another metal plate or sheet, 26, which forms a top surface to separate the underlying elements from the next steam chamber 2 which is mounted immediately above said plate 26.

40 If desired, the relative arrangement of elements as hereinabove described may be continued in tiers in the press, to enable the formation of a plurality of door sections or other articles in one operation of the 45 press, as will be readily understood.

After the relative arrangement of the various elements in the press, as above described, then by operating the follower 5 the elements in the press are subjected to the 50 required pressure to force the plungers or cores 20 to their proper action upon the plastic fireproof composition 19, to mold and produce the desired shape or form of the internal fireproof structure of the door and 55 to effectually compress the same within the mold formed by the external casing plate or sheathing 15 of the completed door structure, and to solidify and harden and dry, under the required pressure and heat, the 60 molded composition 19 in a rigid structure which is of fireproof quality and of low heat conductivity and undeformable by heat.

It will be understood that the press as employed in our improved method may be 65 of any well-known hydraulic or steam power

type, whereby high pressures may be effectively established and maintained for the required determined periods.

In the accompanying illustration of the application of our improved method to the 70 construction of fireproof doors of the character hereinbefore mentioned, the type of door is substantially that shown in our applications for patent Serial No. 815,141, filed January 29, 1914, and Serial No. 815,140, 75 filed January 29, 1914, the completed door of this type as shown in said first-mentioned application being herein illustrated in the cross-section in Fig. 4. A door of this type is constituted by two corresponding half-parts or sections, 27—27, each of which halves comprises the thin metallic casing or sheathing plate 15 forming the external surface of the door at the face or side and at half of the edge portion thereof, the two 80 corresponding half-sections being secured together adhesively or otherwise, as at 28, at the abutting faces of the internal fireproof composition body structure 19 which is molded within the external casing or 85 sheathing 15. The internal body structure of this type of door is molded to form a relatively-thin base portion, 29, extending against and over the area of the base portion 16 of the sheathing plate 15, and thickened 90 edge portions, as at 30, forming continuous blocks or bars extending around the edge portions 17 of the sheathing plate 15, whereby an interior open area or space, as at 95 31, will be formed interiorly of the door, in 100 which open area or space extend bars or blocks, as at 32, in parallel position at suitable intervals and continuously between the thickened edge-portions 30. Therefore, it 105 will be understood that, in constructing this type of door under our present improved method as herein described, the plungers or cores 20 are placed and positioned to produce the desired construction and features of the internal body structure 19 as above 110 set forth. It will further be understood that the half-sections of this type of door are 115 separately formed in the press, according to the improved method herein described, and are assembled and secured together after such half-sections are removed from the press, to form the completed door.

Our improved method is adapted for effectively producing any specific form of molded article or device for use in fireproof 120 building construction, combining an internal fireproof body structure molded and compressed and dried in an external metallic casing or sheathing, it being simply necessary to vary the shape of the mold constituted by the casing plate or sheet 15 and the shape and relative position of the plungers or cores 20 to produce the desired varied 125 forms of any article or device of this type for use in building construction.

The advantages of our improved method of forming fireproof building construction, as herein described, will be readily understood by those skilled in the art to which it 5 appertains. The improvements enable the ready and economical manufacture of the sections of articles for fireproof building construction, which combine an internal fireproof body structure with an external metallic casing or sheathing, in one operation, by directly molding the internal fireproof composition body structure within the mold formed by the external metallic casing or sheathing of the completed article, and also 10 in the one operation the effectual compressing and drying and hardening of the plastic composition, which forms the molded internal fireproof body structure, in permanent association with the external metallic casing 15 or sheathing and in a rigid structure of the requisite density and of low heat conductivity and undeformable by heat.

We do not desire to be understood as limiting ourselves to the detail features and 20 conditions of operation of the steps of the improved process as herein shown and described, as it is manifest that variations and modifications therein may be resorted to, in the adaptation of our invention to varying 25 conditions of use, without departing from the spirit and scope of our invention and improvements. We therefore reserve the right to all such variations and modifications as 30 properly fall within the scope of our invention and the terms of the following claims.

Having thus described our invention, we 35 claim and desire to secure by Letters Patent:

1. The method of forming fireproof building construction, such as doors, trim, or the like, which consists in molding a plastic substance consisting of a fireproof composition, which forms the internal body structure of the completed article, within a mold constituted by a metallic casing or sheathing which forms the external surface of the completed article, and subjecting said plastic composition while in said external surface sheathing mold to the action of plungers or 40 cores and the requisite pressure to produce the desired structural molded shape of the internal body structure and to compress and harden the same in its completed molded shape within the external casing mold to the 45 desired degree of density.

2. The method of forming fireproof building construction, such as doors, trim, or the like, which consists in molding a plastic substance consisting of a fireproof composition, which forms the internal body structure of the completed article, within a mold constituted by a metallic casing or sheathing which forms the external surface of the completed article, and subjecting said plastic composition while in said external surface sheathing 50

mold to the action of plungers, which are perforated to permit the escape of moisture from the plastic composition, and to the action of heat and to the requisite pressure to produce the desired structural molded shape 70 of the internal body structure and to compress and harden and dry the same in its completed molded shape within the external casing mold to the desired degree of density.

3. The method of forming fireproof building construction, such as doors, trim, or the like, which consists in molding a plastic substance consisting of a fireproof composition, which forms the internal body structure of the completed article, within a mold constituted by a metallic casing or sheathing which forms the external surface of the completed article, and subjecting said plastic composition while in said external surface sheathing mold to the action of plungers, which are perforated to permit the escape of moisture from the plastic composition and in association with a sheet of wire netting extending between the bottom of the plungers and the plastic substance to prevent the passage of 90 the latter to said perforations, and to the action of heat and to the requisite pressure to produce the desired structural molded shape of the internal body structure and to compress and harden and dry the same in 95 its completed molded shape within the external casing mold to the desired degree of density.

4. The method of forming fireproof building construction, such as doors, trim, or the like, which consists in molding a plastic substance consisting of a fireproof composition, which forms the internal body structure of the completed article, within a mold constituted by a metallic casing or sheathing which forms the external surface of the completed article, and subjecting said plastic composition while in said external surface sheathing mold to the action of plungers, which are perforated to permit the escape of moisture from the plastic composition and in association with a perforated metallic plate extending across the top of the plungers and intersecting the perforations therein and across the top area 100 of the casing mold to permit the escape of moisture from the plastic composition and to serve as a former for the top surface of the internal composition body structure, and to the action of heat and 105 to the requisite pressure to produce the desired structural molded shape of the internal body structure and to compress and harden and dry the same in its completed molded shape within the external casing 110 mold to the desired degree of density.

5. The method of forming fireproof building construction, such as doors, trim, or the like, which consists in molding a plastic substance consisting of a fireproof compo- 130

sition, which forms the internal body structure of the completed article, within a mold constituted by a metallic casing or sheathing which forms the external surface of the completed article, and subjecting said plastic composition while in said external surface sheathing mold to the action of plungers, which are perforated to permit the escape of moisture from the plastic composition and 5 in association with a perforated metallic plate extending across the top of the plungers and intersecting the perforations therein and across the top area of the casing mold to permit the escape of moisture from 10 the plastic composition and to serve as a former for the top surface of the internal composition body structure, and also in association with a sheet of wire netting extending over the area of said former-plate 15 to permit the escape of moisture from the perforations thereof, and to the action of heat and to the requisite pressure to produce the desired structural molded shape of the internal body structure and to compress 20 and harden and dry the same in its completed molded shape within the external casing mold to the desired degree of density.

6. The method of forming fireproof building construction, such as doors, trim, or the like, which consists in mounting in a suitable press and in association with heated chambers or plates a mold constituted by 25 a metallic casing or sheathing which forms the external surface of the completed article, placing within said external surface sheathing mold a plastic substance consisting of a fireproof composition which forms the internal body structure of the completed 30 article, said casing mold and plastic substance being mounted and placed in association with plungers or cores operative upon

said plastic substance, and then subjecting said elements within the press to the requisite pressure by action of said plungers or cores to mold the plastic substance while in 45 said external surface sheathing mold to produce the desired structural shape of the internal body structure and to the requisite pressure and action of heat to compress 50 and harden and dry the same in its completed molded shape within the external casing mold to the desired degree of density.

7. The method of forming fireproof building construction, such as doors, trim, or the like, which consists in forming two corresponding half-sections each respectively produced by molding a plastic substance consisting of a fireproof composition, which forms the internal body structure of the 60 half-section of the completed article, within a mold constituted by a metallic casing or sheathing which forms the external surface of the half-section of the completed article, and subjecting said plastic composition 65 while in said external surface sheathing mold to the requisite pressure to produce the desired structural shape of the internal body structure and to compress and harden the same in its completed shape within the 70 external casing mold to the desired degree of density, and then securing the corresponding half-sections together with their inner molded surfaces of the internal composition body structures abutting.

In testimony whereof we have signed our names in the presence of the subscribing witnesses.

FRED W. HARGRAVE.
JAMES A. WHEELER.
